Specification for Design.

Patented Aug. 31, 1920.

Application filed February 20, 1920. Serial No. 360,167. Term of patent 14 years.

To all whom it may concern:

Be it known that I, VICTOR GAERTNER, a citizen of the United States, residing at New York city, in the county and State of New York, have invented a new, original, and ornamental Design for a Fruit-Knife Holder or Similar Article, of which the following is a specification, reference being had to the accompanying drawings, forming a part thereof, and in which—

Figure 1 is a side elevation;
Fig. 2 an edge view, and
Fig. 3 a plan view of a fruit knife holder embodying my design.

I claim:

The ornamental design for a fruit knife holder or similar article, as shown.

VICTOR GAERTNER.
